ELECTRIC SWITCH

Filed Sept. 29, 1930

UNITED STATES PATENT OFFICE

GEORGE J. MEUER, OF MILWAUKEE, WISCONSIN, ASSIGNOR TO CUTLER-HAMMER, INC.,
OF MILWAUKEE, WISCONSIN, A CORPORATION OF DELAWARE

ELECTRIC SWITCH

Application filed September 29, 1930. Serial No. 485,021.

This invention relates to improvements in electric switches, and more particularly to rotary switches of relatively low current carrying capacity.

An object of the invention is to provide improved and simplified switches of the aforementioned character.

Another object is to provide a group of elements the major number of which may be utilized in constructing switches of different types, such as single- or multiple-circuit controlling switches.

Another object is to provide switches of the aforementioned character having stationary and movable contacts of improved form.

Other objects and advantages of the invention will hereinafter appear.

The accompanying drawings illustrate certain embodiments of the invention which will now be described, it being understood that the embodiments illustrated are susceptible of modification without departing from the scope of the appended claims.

In the drawings,

Figure 1 is a vertical sectional view of a three-position switch constructed in accordance with my invention.

Fig. 2 is a bottom plan view of the switch shown in Fig. 1.

Fig. 3 is a perspective view, in separated relation, of the several parts of the switch shown in Fig. 1.

Fig. 4 is a fragmentary sectional view of a switch having a modified form of actuating shaft and bushing.

Fig. 5 is an enlarged fragmentary sectional view illustrating the manner of mounting the stationary contacts flush with the upper surface of the insulating base.

Fig. 6 is a perspective view of a slightly modified form of switch base adapted for assembly with other of the parts shown in Fig. 1 to provide a two-position switch, that is, a switch having one on position and one off position.

Fig. 7 is an enlarged elevational view of the stop post or lug shown in Fig. 6.

Fig. 8 is a bottom plan view of a four-

position switch constructed in accordance with my invention, and

Fig. 9 is a view partly in vertical section, on the line 9—9 of Fig. 8, and partly in side elevation, showing the manner of securing certain of the terminal plates against movement relatively to the base.

Referring first to the device illustrated in Figs. 1, 2, 3 and 5, the numeral 15 designates a relatively thin but relatively rigid base consisting of a flat punched plate of insulating material,—said base being preferably of substantially circular contour. Base 15 is provided with a central circular opening 16 and a multiplicity of openings 17, 18, 19, 20, 21 and 22 arranged symmetrically thereabout.

Those ends of openings 18, 19, 21 and 22 which open to the upper surface of base 15 are preferably provided with flared and countersunk walls, as indicated in Fig. 1 and as shown in detail in Fig. 5. Said openings are thus adapted to receive, in a flush relation with the upper surface of base 15, the flared upper ends 18^b, 19^b, 21^b and 22^b of suitable eyelets,—the opposite ends of said eyelets being adapted to penetrate corresponding openings in terminal plates 18^c, 19^c and 21^c and being upset over the latter to secure the same to the lower surface of base 15. The respective terminal plates are provided with binding screws 18^d, 19^d and 21^d, and the base 15 is provided with suitable openings to accommodate the shanks of said screws.

As will be understood the flared ends 18^b, 19^b, 21^b and 22^b form the stationary contacts of the switch, the arrangement being such that contacts 18^b, 21^b may be bridged, or contacts 19^b, 22^b may be bridged, or all of said contacts may be disengaged by the movable contactor. The movable bridging contactor of the switch preferably comprises a flat punched plate 23 of insulating material,—said plate being of substantially elliptical contour but having slightly pointed ends. Plate 23 is provided with an elongated intermediate opening 24 and openings 25 and 26 adjacent to opposite ends thereof.

Adapted to lie against the lower face of plate 23 is a flat punched sheet metal plate 27 having an intermediate opening 28 regis-

tering with but considerably larger than the opening 24,—plate 27 also having openings 29 and 30 adapted to register with the openings 25 and 26, respectively. A pair of ⁵ vex-headed hollow-shank rivets 31 and 32 are provided,—the shanks of said rivets being adapted to penetrate the respective pairs of registering openings 29, 25 and 30, 26 in plates 27 and 23, and being upset over the latter (as shown in Fig. 1) to rigidly secure ¹⁰ said parts to each other.

Rigidly secured to base 15 in a well known manner, as by means of integral lugs 33^a adapted to register with suitable notches in ¹⁵ the periphery of said base and bent inwardly over the lower surface of the latter, is a substantially dome-shaped metal housing 33 having a central opening 34, preferably of polygonal contour, to receive the reduced lower ²⁰ end 35 of an externally threaded hollow metal bushing 36,—said end 35 being upset over the inner surface of housing 33 (as shown in Fig. 1) to rigidly secure said bushing and housing to each other.

²⁵ Rotatable within the bushing 36 is a switch actuating shaft 37 which preferably consists of a flat sheet metal punching. Shaft 37 is provided with a pair of lateral projections 38 and 39 which are adapted to bear against ³⁰ the lower end surface 40 of the bushing. One end 41 of the shaft projects upwardly beyond the bushing and is adapted to have fitted thereonto a metal knob 42 having a cylindrical recess 43. Knob 42 has a shank or ³⁵ neck portion which is swaged at diametrically opposite points to upset the same against the opposite edges of end portion 41 of the shaft, whereby said knob and shaft are rigidly and permanently interlocked against ⁴⁰ movement relatively to each other, as indicated at 44. As shown the lower surface 45 of said shank is adapted to bear against the upper end of bushing 36.

The lower portion 46 of shaft 37 is adapted ⁴⁵ to extend downwardly through the opening 24 in insulating plate 23 for driving engagement with the walls of said opening,—it being noted that the opening 28 in metal plate 27 is sufficiently large to insure against contact of the latter with said shaft. The lower ⁵⁰ end of portion 46 is of reduced width, as indicated at 47, to fit within the central opening 16 in base 15, whereby the lower end of the shaft is properly centered.

⁵⁵ Interposed between the arms 38, 39 of the shaft and the upper surface of insulating plate 23 is a coiled compression spring 48, said spring being normally compressed to a predetermined degree by assembly of the switch ⁶⁰ parts in the manner aforescribed. This spring is adapted to bias the bridging contactor into engagement with the upper surface of base 15, so that upon rotation of shaft 37 the bridging contactor tends to snap into ⁶⁵ engagement with the diametrically opposed

pairs 18^b, 21^b or 19^b, 22^b of stationary contacts or into engagement with the diametrically opposed pairs of openings 17, 20 in base 15. The switch as so constructed is adapted to complete alternative electric circuits in its respective on positions, or to interrupt both of said circuits in its off position. ⁷⁰

I have shown a stop lug 21^c formed integrally with the terminal plate 21^c and adapted to extend upwardly through a suitable opening 49 in base 15 into the path of the insulating plate 23 forming part of the bridging contactor. With this arrangement it will be seen that the bridging contactor (see ⁷⁵ Fig. 3) may be moved in a clockwise direction from its off or neutral position into engagement with the pairs of stationary contacts 22^b, 19^b and 21^b, 18^b sequentially, and thereafter in a reverse direction,—the movement of said contactor in each direction being limited to an arc of less than one hundred eighty degrees. Obviously the location of the stop lug may be changed if desired to provide a different switching combination. ⁸⁰ Thus by locating a stop lug in outwardly offset relation between either of the two groups of stationary contacts 21^b, 22^b and 18^b, 19^b, the contactor may be constrained to move from either of its on positions to an intermediate ⁸⁵ off position,—such a stop lug being formed integrally with terminal plate 21^c or integrally with either of the terminal plates 18^c or 19^c. ⁹⁰

The base 15^a illustrated in Fig. 6 is adapted ¹⁰⁰ to function in combination with the contactor and actuator illustrated in Fig. 1 to provide a switch having a single on position and a single off position,—the openings 17^a and 20^a being adapted to receive the contactor in its off position, and corresponding in location and function to the openings 17 and 20 of Fig. 3. The openings 50 and 51 are located in a line at right angles to the line of openings 17^a and 20^a, and the eyelets ¹⁰⁵ 50^b, 51^b, terminal plates 50^c, 51^c and binding screws 50^d, 51^d are like the corresponding parts of the switch aforescribed. ¹¹⁰

The stop lug for the bridging contactor might be formed integrally with one of the ¹¹⁵ terminal plates 50^c or 51^c, but I prefer to employ a separately formed piece 52, Figs. 6 and 7, which is provided with a cylindrical portion 52^a to be inserted within a suitably shaped and properly located opening in ¹²⁰ base 15^a, so that the intermediate flange or shoulder 52^b will rest upon the upper surface of base 15^a,—the lower end of portion 52^a being upset over the lower face of base 15^a, as indicated at 52^c, to secure said stop lug in ¹²⁵ position.

The switch base 15^b illustrated in Figs. ¹³⁰ 8 and 9 is provided with a central opening 16 and with eight openings arranged symmetrically thereabout,—the openings 17^b

and 20^b being adapted to receive and retain the contractor in its off position, and the other openings being provided with eyelets 53, 54, 55, 56, 57 and 58 of the character 5 aforescribed. Terminal plates 53^a, 54^a and 55^a are secured to the base by the upset lower ends of eyelets 53, 54 and 55, and the common terminal plate 56^a is secured to said base by the upset lower ends of eyelets 56, 10 57 and 58. The terminal plates extend outwardly beyond the periphery of base 15^b and are respectively provided with binding screws 53^b, 54^b, 55^b and 56^b arranged in the manner shown. Terminal plates 53^a 15 54^a and 55^a are additionally provided with extruded projections or bosses 53^c, 54^c and 55 which extend upwardly into corresponding openings in the base, to insure against displacement of said terminal plates with respect to the base,—one of said openings being 20 shown at 54^a in Fig. 9.

The common terminal plate 56^a is provided with an integral lug 56^c which extends upwardly through a corresponding opening 25 15^c in base 15^b in the path of the bridging contractor to limit the degree of rotary movement of the latter. Thus the contractor may be moved from its off or neutral position into engagement with the pairs of eyelet contacts 53, 56; 54, 57 and 55, 58 sequentially and thereafter in a reverse direction. Thus assuming wiring of the switch to include the resistance elements 59 and 60 between the binding screws 53^b, 64^b and 54^b, 30 55^b respectively, it will be apparent that the switch may be so wired as to provide for inclusion of both resistance elements in the circuit of a suitable translating device (such as a fan) upon bridging of eyelet contacts 53 and 56, and for inclusion of resistance element 60 only upon bridging of eyelet contacts 54 and 57, and for connection of such translating device directly across the line upon bridging of eyelet contacts 55 and 58. 35 40 45 It will be understood that the other elements of the switch illustrated in Figs. 8 and 9 may be identical with the corresponding elements aforescribed.

In Fig. 4 I have illustrated a modified 50 form of switch,—the modification merely involving use of a relatively shorter bushing 36^a and a correspondingly shorter actuating shaft 37^a.

As shown in Fig. 3 the upper surface of knob 42 is preferably provided with an arrow 61 or other similar marking which may be utilized in conjunction with suitable legends or indicia upon the mounting board or 55 60 65 panel (not shown) of the switch to indicate the position of the bridging contractor of the switch.

The bushings 36, 36^a are preferably provided with clamping nuts 62 and 63 whereby the switches are adapted for one-hole mount-

ing in panels or supports (not shown) of different thicknesses.

What I claim as new and desire to secure by Letters Patent is:

1. In an electric switch, in combination, an externally threaded hollow metal bushing, an actuating shaft comprising a flat punched sheet metal member having one end penetrating said bushing and projecting upwardly therebeyond, a metal knob having a hollow shank to receive the upper end of said shaft, said shank and said shaft end being jointly swaged to permanently interlock the same against movement relatively to each other, said shank being adapted to bear against one end of said bushing, said shaft having an integral lateral projection adjacent to the other end of said bushing to bear against the latter, a contractor slidably mounted upon the lower end of said shaft and interlocked with the latter for rotation thereby, a coiled compression spring interposed between said lateral projection and said contractor, and an insulating base supported in spaced relation to said bushing and adapted to retain said contractor in assembled relation to said shaft. 50 55 60 65 70 75 80 85 90 95

2. In an electric switch, in combination, an externally threaded hollow metal bushing, an actuating shaft comprising a flat punched sheet metal member having one end penetrating said bushing and projecting upwardly therebeyond, a metal knob having a hollow shank to receive the upper end of said shaft, said shank and said shaft end being jointly swaged to permanently interlock the same against movement relatively to each other, said shank being adapted to bear against one end of said bushing, said shaft having an integral lateral projection adjacent to the other end of said bushing to bear against the latter, a contractor slidably mounted upon the lower end of said shaft and interlocked with the latter for rotation thereby, a coiled compression spring interposed between said lateral projection and said contractor, and an insulating base supported in spaced relation to said bushing and adapted to retain said contractor in assembled relation to said shaft. 100 105 110 115 120 125

3. In an electric switch, in combination, an externally threaded hollow metal bushing, an actuating shaft comprising a flat punched sheet metal member having one end penetrating said bushing and projecting upwardly therebeyond, a metal knob having a hollow shank to receive the upper end of said shaft, said shank and said shaft end being jointly swaged to permanently interlock the same against movement relatively to each other, said shank being adapted to bear against one end of said bushing, said shaft having an integral lateral projection adjacent to the 125

other end of said bushing to bear against the latter, a contactor slidably mounted upon the lower end of said shaft and interlocked with the latter for rotation thereby, a coiled compression spring interposed between said lateral projection and said contactor, an insulating base supported in spaced relation to said bushing and adapted to retain said contactor in assembled relation to said shaft, said base having stationary contact elements to be engaged and disengaged by said contactor respectively upon rotation of said shaft, said contact elements each comprising an eyelet having a flared end thereof arranged in flush relation to the upper surface of said base, and wiring terminal plates over which the other ends of the respective eyelets are upset to secure said terminal plates to the base.

4. In an electric switch, in combination, an externally threaded hollow metal bushing, an actuating shaft comprising a flat punched sheet metal member having one end penetrating said bushing and projecting upwardly therebeyond, a metal knob having a hollow shank to receive the upper end of said shaft, said shank and said shaft end being jointly swaged to permanently interlock the same against movement relatively to each other, said shank being adapted to bear against one end of said bushing, said shaft having an integral lateral projection adjacent to the other end of said bushing to bear against the latter, a contactor slidably mounted upon the lower end of said shaft and interlocked with the latter for rotation thereby, a coiled compression spring interposed between said lateral projection and said contactor, and a flat punched plate of insulating material supported in spaced relation to said bushing, and adapted to retain said contactor in assembled relation to said shaft, said plate having a central opening within which a reduced end of said shaft is adapted to bear for centering of the latter.

5. In an electric switch, in combination, a base comprising a flat punched plate of insulating material, said plate having a central opening and a multiplicity of openings arranged symmetrically around said central opening, eyelets penetrating certain of said openings and having flared ends arranged flush with the upper surface of said base, wiring terminal plates positioned on the lower surface of said base and secured thereto by said eyelets respectively, binding screws engaging tapped openings in said terminal plates, openings in said base to accommodate the shanks of said binding screws, a metal housing rigidly secured to said base, an externally threaded hollow metal bushing secured to said housing, a flat punched sheet metal shaft having projecting portions to bear against one end of said bushing, a knob rigidly secured to said shaft and adapted to bear against the opposite end of said bushing,

the lower end of said shaft being adapted to bear within said central opening in the base to be centered thereby, a punched plate of insulating material slidable upon said shaft but interlocked against rotation with respect thereto, convex-headed rivets secured to said insulating plate for cooperation with said eyelets respectively to make or break circuit therebetween, said rivets having a bus member extending therebetween, and a coiled compression spring interposed between a part of said shaft and said insulating plate to bias said rivet heads into engagement with said base.

6. In an electric switch, in combination, a base comprising a flat punched plate of insulating material, said plate having a central opening and a multiplicity of openings arranged symmetrically around said central opening, eyelets penetrating certain of said openings and having flared ends arranged flush with the upper surface of said base, wiring terminal plates positioned on the lower surface of said base and secured thereto by said eyelets respectively, binding screws engaging tapped openings in said terminal plates, openings in said base to accommodate the shanks of said binding screws, a metal housing rigidly secured to said base, an externally threaded hollow metal bushing secured to said housing, a flat punched sheet metal shaft having projecting portions to bear against one end of said bushing, a knob rigidly secured to said shaft and adapted to bear against the opposite end of said bushing, the lower end of said shaft being adapted to bear within said central opening in the base to be centered thereby, a punched plate of insulating material slidable upon said shaft but interlocked against rotation with respect thereto, convex-headed rivets secured to said insulating plate for cooperation with said eyelets respectively to make or break circuit therebetween, said rivets having a bus member extending therebetween, a coiled compression spring interposed between a part of said shaft and said insulating plate to bias said rivet heads into engagement with said base, and a stop projecting upwardly from said base in the path of said insulating plate to limit the degree of rotation of the latter in opposite directions respectively.

7. In an electric switch, in combination, a base comprising a flat punched plate of insulating material, said plate having a central opening and a multiplicity of openings arranged symmetrically around said central opening, eyelets penetrating certain of said openings and having flared ends arranged flush with the upper surface of said base, wiring terminal plates positioned on the lower surface of said base and secured thereto by said eyelets respectively, binding screws engaging tapped openings in said terminal plates, openings in said base to accommodate

- the shanks of said binding screws, a metal housing rigidly secured to said base, an externally threaded hollow metal bushing secured to said housing, a flat punched sheet 5 metal shaft having projecting portions to bear against one end of said bushing, a knob rigidly secured to said shaft and adapted to bear against the opposite end of said bushing, the lower end of said shaft being adapted 10 to bear within said central opening in the base to be centered thereby, a punched plate of insulating material slideable upon said shaft but interlocked against rotation with respect thereto, convex-headed rivets secured 15 to said insulating plate for cooperation with said eyelets respectively to make or break circuit therebetween, said rivets having a bus member extending therebetween, a coiled compression spring interposed between a part 20 of said shaft and said insulating plate to bias said rivet heads into engagement with said base, and a stop projecting upwardly from said base in the path of said insulating plate to limit the degree of rotation of the 25 latter in opposite directions respectively, said stop comprising a lug formed integrally with one of said terminal plates.
8. In an electric switch, in combination, a contactor comprising a punched plate of insulating material, a punched metal plate adapted to lie against one face of said insulating plate, said plates having alined elongated intermediate openings and alined openings at opposite ends thereof, a pair of headed rivets having hollow shanks adapted 30 to penetrate said last mentioned openings and upset over said insulating plate to secure said parts to each other, and a punched sheet metal actuating shaft having a portion penetrating said intermediate openings for driving engagement with said insulating plate, the intermediate opening in said metal plate being relatively large to provide clearance for 35 said shaft.
9. In an electric switch, in combination, a contactor comprising a punched plate of insulating material, a punched metal plate adapted to lie against one face of said insulating plate, said plates having alined elongated intermediate openings and alined openings at opposite ends thereof, a pair of headed rivets having hollow shanks adapted 40 to penetrate said last mentioned openings and upset over said insulating plate to secure said parts to each other, a punched sheet metal actuating shaft having a portion penetrating said intermediate openings for driving engagement with said insulating plate, the intermediate opening in said metal plate being relatively large to provide clearance for 45 said shaft, a base comprising a punched plate of insulating material against which said contactor is adapted to bear, said base having a central opening to accommodate the lower end of said shaft, a plurality of 50 symmetrally arranged openings in said base, eyelets in certain of said openings arranged flush with the upper surface of said base, and wiring terminal plates located on the lower surface of said base and secured thereto by said eyelets respectively, certain of said terminal plates being common to a group 55 of said eyelets.
10. In an electric switch, in combination, a contactor comprising a punched plate of insulating material, a punched metal plate adapted to lie against one face of said insulating plate, said plates having alined elongated intermediate openings and alined openings at opposite ends thereof, a pair of headed rivets having hollow shanks adapted 60 to penetrate said last mentioned openings and upset over said insulating plate to secure said parts to each other, a punched sheet metal actuating shaft having a portion penetrating said intermediate openings for driving engagement with said insulating plate, the intermediate opening in said metal plate being relatively large to provide clearance for 65 said shaft, a base comprising a punched plate of insulating material against which said contactor is adapted to bear, said base having a central opening to accommodate the lower end of said shaft, a plurality of 70 symmetrally arranged openings in said base, eyelets in certain of said openings arranged flush with the upper surface of said base, and wiring terminal plates located on the lower surface of said base and secured thereto by said eyelets respectively, certain of said terminal plates being common to a group of said eyelets.
11. In an electric switch, in combination, a contactor comprising a punched plate of insulating material, a punched metal plate adapted to lie against one face of said insulating plate, said plates having alined elongated intermediate openings and alined openings at opposite ends thereof, a pair of headed rivets having hollow shanks adapted 75 to penetrate said last mentioned openings and upset over said insulating plate to secure said parts to each other, a punched sheet metal actuating shaft having a portion penetrating said intermediate openings for driving engagement with said insulating plate, the intermediate opening in said metal plate being relatively large to provide clearance for 80 said shaft, a base comprising a punched plate of insulating material against which said contactor is adapted to bear, said base having a central opening to accommodate the lower end of said shaft, a plurality of 85 symmetrally arranged openings in said base, eyelets in certain of said openings arranged flush with the upper surface of said base, and wiring terminal plates located on the lower surface of said base and secured thereto by said eyelets respectively, certain of said terminal plates being common to a group of said eyelets.
12. In an electric switch, in combination, a contactor comprising a punched plate of insulating material, a punched metal plate adapted to lie against one face of said insulating plate, said plates having alined elongated intermediate openings and alined openings at opposite ends thereof, a pair of headed rivets having hollow shanks adapted 90 to penetrate said last mentioned openings and upset over said insulating plate to secure said parts to each other, a punched sheet metal actuating shaft having a portion penetrating said intermediate openings for driving engagement with said insulating plate, the intermediate opening in said metal plate being relatively large to provide clearance for 95 said shaft, a base comprising a punched plate of insulating material against which said contactor is adapted to bear, said base having a central opening to accommodate the lower end of said shaft, a plurality of 100 symmetrally arranged openings in said base, eyelets in certain of said openings arranged flush with the upper surface of said base, and wiring terminal plates located on the lower surface of said base and secured thereto by said eyelets respectively, certain of said terminal plates being common to a group of said eyelets.
13. In an electric switch, in combination, a contactor comprising a punched plate of insulating material, a punched metal plate adapted to lie against one face of said insulating plate, said plates having alined elongated intermediate openings and alined openings at opposite ends thereof, a pair of headed rivets having hollow shanks adapted 105 to penetrate said last mentioned openings and upset over said insulating plate to secure said parts to each other, a punched sheet metal actuating shaft having a portion penetrating said intermediate openings for driving engagement with said insulating plate, the intermediate opening in said metal plate being relatively large to provide clearance for 110 said shaft, a base comprising a punched plate of insulating material against which said contactor is adapted to bear, said base having a central opening to accommodate the lower end of said shaft, a plurality of 115 symmetrally arranged openings in said base, eyelets in certain of said openings arranged flush with the upper surface of said base, and wiring terminal plates located on the lower surface of said base and secured thereto by said eyelets respectively, certain of said terminal plates being common to a group of said eyelets.
14. In an electric switch, in combination, a contactor comprising a punched plate of insulating material, a punched metal plate adapted to lie against one face of said insulating plate, said plates having alined elongated intermediate openings and alined openings at opposite ends thereof, a pair of headed rivets having hollow shanks adapted 120 to penetrate said last mentioned openings and upset over said insulating plate to secure said parts to each other, a punched sheet metal actuating shaft having a portion penetrating said intermediate openings for driving engagement with said insulating plate, the intermediate opening in said metal plate being relatively large to provide clearance for 125 said shaft, a base comprising a punched plate of insulating material against which said contactor is adapted to bear, said base having a central opening to accommodate the lower end of said shaft, a plurality of 130 symmetrally arranged openings in said base, eyelets in certain of said openings arranged flush with the upper surface of said base, and wiring terminal plates located on the lower surface of said base and secured thereto by said eyelets respectively, certain of said terminal plates being common to a group of said eyelets.

In witness whereof, I have hereunto subscribed my name.

GEORGE J. MEUER.
